Primary Examiner — Darlington Ly*Assistant Examiner* — Nasim Abdulaziz Ali(74) *Attorney, Agent, or Firm* — Saidman DesignLaw Group, LLC(57) **CLAIM**

The ornamental design for a tire, as shown and described.

DESCRIPTION

FIG. 1 is a front perspective view of a tire showing our new design; and,

FIG. 2 is a partial, enlarged view thereof.

The broken lines illustrate boundaries which form no part of the claimed design. In FIG. 1, the blurred portions in the drawing form no part of the claimed design.

1 Claim, 2 Drawing Sheets(56)
